(57) **CLAIM**

The ornamental design of a transmitter for electromagnetic flowmeter, as shown and described.

DESCRIPTION

FIG. 1 is a front view of a first embodiment of a transmitter for electromagnetic flowmeter;

FIG. 2 is a rear side view of the first embodiment of the transmitter for electromagnetic flowmeter;

FIG. 3 is a right side view of the first embodiment of the transmitter for electromagnetic flowmeter;

FIG. 4 is a left side view of the first embodiment of the transmitter for electromagnetic flowmeter;

FIG. 5 is a top view of the first embodiment of the transmitter for electromagnetic flowmeter; and,

FIG. 6 is a bottom view of the first embodiment of the transmitter for electromagnetic flowmeter.

The surface shading lines in the drawings depict the character or contour of the surfaces represented and form no part of the claimed design.

The dashed lines in the drawings depict the environment and boundaries and form no part of the claimed design.
